UNITED STATES PATENT OFFICE.

FREDERICK A. BREDEL, OF ST. LOUIS, MISSOURI.

COKING RETORT OVEN.

Application filed March 7, 1924. Serial No. 697,559.

This invention relates to coking retort ovens, and particularly, to a coking retort oven of the kind described in U. S. Patent No. 1,374,546, to Joseph Becker, dated April 5 12, 1921, wherein the side walls of each coking chamber contains vertical flame flues or combustion flues whose upper ends communicate with horizontally-disposed collection flues or bus flues that are connected together 10 in pairs in such a way that the gases or products of combustion used to heat each coking chamber can be directed upwardly through the combustion flues in one side wall of a coking chamber, then across the 15 upper end of said chamber, and thereafter downwardly through the combustion flues in the other side wall of said chamber. Each horizontal bus flue increases gradually in depth from its outer ends towards its middle 20 so as to distribute the flow of the gases equally through the vertical combustion flues in the side walls of the coking chamber with which said bus flues communicate, and said bus flues are arranged in the extreme upper 25 end portions of the side walls of the coking chambers. Due to the fact that the bus flues of prior coking retort ovens of this general type are located in the side walls of the gas spaces, at the upper ends of the coking 30 chambers, there is a tendency for the gases that are evolved from the coal to become overheated, thereby resulting in the formation of large quantities of lamp black.

The main object of my invention is to 35 provide a coking retort oven that will produce a larger quantity and a better quality of fuel or illuminating gas from a given quantity of coal than can be obtained with an oven of the construction shown in said 40 Becker patent.

Another object of my invention is to provide a coking retort oven that has the desirable characteristics and features of the oven described in said Becker patent, but 45 which is constructed in such a way that there is little liability of the gases evolved from the coal becoming superheated, due to too high temperature of the side walls of the gas spaces at the upper ends of the coking 50 chambers. To this end I propose to arrange the horizontal bus flues of a coking retort oven of the kind described in said Becker patent at a lower level than the gas spaces at the upper ends of the coking chambers, thereby preventing the side walls of

said gas spaces from becoming overheated, as is liable to occur if the products of combustion used to heat the oven are caused to circulate through flues in the side walls of said gas spaces. The bus flues are tapered in such a way that each bus flue increases gradually in depth from its opposite ends towards the middle of same, but instead of having the top walls of the bus flues slope upwardly, as illustrated and described in 60 said Becker patent, I provide each bus flue of my improved oven with a top wall that is disposed horizontally, or substantially so, and a bottom wall that slopes downwardly from the opposite ends of the flue towards 65 the middle of same, thereby causing the hottest zone of the coking chamber to be located at a point well below the top surface of the coal in said chamber.

Figure 1 of the drawings is a vertical 75 cross sectional view of a portion of a coking retort oven constructed in accordance with my invention.

Figure 2 is a vertical longitudinal sectional view of a portion of the oven, taken 80 on the line 2-2 of Figure 1, illustrating one of the coking chambers and the vertically-disposed combustion flues and bus flues in the side walls of said chamber; and

Figure 3 is a vertical longitudinal sectional view, taken on the line 3-3 of Figure 1, illustrating the gas passageway at the upper end of the coking chamber that joins the horizontal bus flues that are associated with said chamber.

Referring to the drawings, A designates a vertically-disposed coking chamber that extends transversely of the oven, B designates a plurality of vertically-disposed fire flues or combustion flues in each side wall of said coking chamber, and C designates horizontal bus flues or collection flues in the side walls of the coking chamber that communicate with the upper ends of the combustion flues B. The combustion flues B in each side 95 wall of the coking chamber communicate with a separate horizontal bus flue C and the two bus flues that are associated with the coking chamber are connected together by a gas passageway D, as shown in Figure 3, thereby 100 permitting the gases or products of combustion used to operate the oven to be directed upwardly through the combustion flues B at one side of the coking chamber, then across 105 the upper end of said chamber through the 110

passageway D, and then downwardly through the combustion flues B at the other side of said chamber.

The coking chamber A is adapted to be filled with coal α up to a point at approximately the same level as the top walls 1 of the horizontal bus flues C, thus leaving a space between the top surface of the coal α and the top wall of the coking chamber A (designated by the reference character 2 in Figure 3) for the gases that are evolved from the coal. Consequently, when the oven is in operation the products of combustion used to heat the coking chamber A will circulate around the portions of the side walls of said chamber that contact with the coal, but will not circulate around the side walls of the gas space at the upper end of the coking chamber A. Therefore, there is little liability of the gases evolved from the coal being superheated or overheated to such an extent as to result in the formation of large quantities of lamp black.

Each horizontal bus flue C is tapered from its ends towards its middle, as shown in Figure 1, but instead of obtaining the taper by sloping the top wall of said flue upwardly, as in the Becker patent, I provide each bus flue of my improved oven with a top wall 1 that is disposed substantially horizontally and a bottom wall that slopes downwardly from the opposite ends of said flue towards the middle of the flue. Accordingly my improved oven is distinguished from the oven described in said Becker patent, not only by reason of the fact that the horizontal bus flues in the side walls of the coking chamber are located at a point below, or approximate-

ly below, the level of the coal in the coking chamber, but also by reason of the fact that said bus flues are of such cross-sectional shape that the deepest portion of each bus flue extends downwardly away from the gas space at the upper end of the coking chamber, instead of extending upwardly into the side wall of said gas space.

While I have herein illustrated my invention embodied in a cross regenerative coking oven, I wish it to be understood that my invention is applicable to a recuperative coke oven of the kind wherein the combustion gases ascend one set of heating flues at one side of the coking chamber and descend the corresponding flues at the opposite side of said chamber without reversing.

Having thus described my invention, what I claim as new and desire to secure by Letters Patent is:

A coking retort oven provided with a coking chamber, horizontal bus flues in each of the side walls of said coking chamber having horizontally-disposed top walls arranged at a point substantially below the top wall of said coking chamber and having inclined bottom walls that slope downwardly from the ends of each of said bus flues towards the middle portions thereof, vertical combustion flues in the side walls of said coking chamber whose upper ends communicate with said bus flues, and a passageway extending transversely across the top wall of the coking chamber for establishing communication between said bus flues at the middle portions of each of the latter.

FREDERICK A. BREDEL.
